[57] **CLAIM**

The ornamental design for a bicycle saddle, as shown and described.

DESCRIPTION

FIG. 1 is a top view of a bicycle saddle in accordance with the invention;

FIG. 2 is a left side elevation view of a bicycle saddle showing FIG. 1, the right side being identical;

FIG. 3 is a front elevation view of a bicycle saddle illustrated in FIG. 1;

FIG. 4 is a rear elevation view of a bicycle saddle illustrated in FIG. 1;

FIG. 5 is a bottom view of a bicycle saddle illustrated in FIG. 1; and,

FIG. 6 is a right side elevation view of a bicycle saddle illustrated in FIG. 1.

The broken lines shown in FIGS. 2–6 are for illustrative purposes only and form no part of the claimed design.
